LIGHT SUPPORTING POLE

Jerry D. Sorrentino, Scotch Plains, N.J., assignor to Pfaff
& Kendall, Newark, N.J., a corporation of New Jersey

Filed Aug. 29, 1958, Ser. No. 52,447

Term of patent 14 years

(Cl. D48—31)

Fig. 1 is an elevational view of a light supporting pole embodying my new design; and

Fig. 2 is a top plan view thereof.

Fig. 3 is an enlarged sectional view thereof taken on line 3—3 of Fig. 1.

I claim:

The ornamental design for a light supporting pole, as shown.
